UNITED STATES PATENT OFFICE

155,852

DESIGN FOR A COVERING PAPER FOR CANDY BOXES OR THE LIKE

Egon Volz, New York, N. Y., assignor to Ellens
Chocolates, a firm composed of Ellen Simon,
Rosy Simon, Carl Simon, and Peter C. Simon,
New York, N. Y.

Application January 22, 1948, Serial No. 143,977

Term of patent 14 years

(Cl. D59—2)

To all whom it may concern:

Be it known that I, Egon Volz, a citizen of Germany, resident of the city of New York, in the county of New York and State of New York, have invented a new, original, and ornamental Design for a Covering Paper for Candy Boxes or the like, of which the following is a specification, reference being had to the accompanying drawing, forming part thereof.

In the drawing the figure is a plan view of the covering paper for candy boxes or the like, showing my new design.

A design unit is outlined by the broken lines. Said unit is repeated over the covering paper for candy boxes or the like as indicated by the extensions beyond the unit boundaries.

I claim:

The ornamental design for a covering paper for candy boxes or the like, as shown and described.

EGON VOLZ.
